UNITED STATES PATENT OFFICE.

HUGO KARL SAKOWSKI, OF NEW YORK, N. Y.

PIN.

Application filed July 14, 1926. Serial No. 122,397.

This invention relates to pins; and its object is to provide certain improvements of construction which impart to the pin the advantages both of an ordinary pin, such as 5 smallness, lightness, cheapness and ready applicability for various purposes, and of a so-called safety pin, such as reliability and absence of risk of accidents, so that the improved pin will be useful for domestic purposes as well as in the office, shop and factory line.

Ordinary straight and smooth pins in general use for joining together cloth, letters, documents and the like are objectionable, since they frequently detach from the material and get lost and give rise to injuries.

My invention aims to remedy this defect by constructing a pin comprising a head and 20 a shank in such a manner that the frictional surface effect thereof will be greatly increased. According to my invention, the shank of the pin is bent to form a single locking portion and a single guiding portion 25 which lie in the plane of the shank itself and which are respectively located comparatively near the head and point of the pin. These two portions are positioned at an angle to each other and to the axis of the 30 shank, the extent of the angle formed between the first-named portion and the axis determining the degree of locking action, so that by making the angle wider or narrower the locking action will be increased or decreased. The locking portion is quite small 35 and extends outwardly from the foot of the head end portion of the shank; whereas the guiding section, which is longer than the locking portion, extends inwardly from the 40 outer end of the latter portion to the upper end or top of the point end portion, the two main shank portions having a common axis.

The point end portion can be easily pushed through the material to be pinned, 45 and the insertion of the pin can be continued until its locking portion has moved through the material, which is assisted, as will be understood, by the provision of the comparatively longer guiding portion. To withdraw the pin, however, an actual pull must be exerted on its head end in order to overcome the resistance offered to its movement by the angularly-positioned locking portion, and it is due to this resistance that any danger 50 of the pin accidentally working its way out of the material is entirely obviated.

In the accompanying drawing:

Figure 1 is a side view of one form which the pin may take in practice and in which the locking and guiding portions are quite short;

Fig. 2 is a similar view of a second form, embodying a slightly longer locking portion and a much longer guiding portion;

Fig. 3 is a side view of a third form, in which the locking portion is of approximately the same length as in Fig. 1, whereas the guiding portion has an even longer length than in Fig. 2;

Fig. 4 is a cross-section on line 4—4, 70 Fig. 1.

Referring more particularly to said drawings, it will be observed that the pin comprises four distinct portions or sections, viz: a head end section 2, a locking section 3, a 75 guiding section 4 and a point end section 5. The top section 2 is straight in the construction illustrated (though it may, of course, be bent or curved) and its outer end is shaped to form a head 1; and this section, as well as the other sections specified, or any 80 of them, may be of circular or other approved cross-section. The lower or bottom section 5 is likewise represented as straight and as terminating in a point 6, but may be 85 bent or curved, and both it and the section 2 may have any desired length.

The locking and guiding sections 3 and 4 embody the most important features of my invention, and are designed to serve the purposes indicated by their respective names. The locking section is located at the foot of the head end section 2 and extends outwardly therefrom at an angle, as shown; and such angle, which is indicated at 7 and 90 95 which will be termed the locking angle, may be varied at will within certain limits so as to regulate or adjust the resistance which it opposes to the withdrawal of the pin. In Figs. 1 and 3, the locking section 3, which is of virtually the same length in both instances, is extremely short; whereas in Fig. 2 it is about twice as long as in Figs. 1 and 3. It may be made even shorter than in the first construction; or it may be given a 100 greater length than in Fig. 2, according to conditions; and in like manner, the locking angle 7 may be made narrower or wider, as preferred.

The guiding section 4 extends backwardly 110 or inwardly from the lower or outer end of the locking section 3 to the upper end of the

point end section 5 and, like the section 3, may be of various lengths according to circumstances. It should, however, in any case, be longer than section 3, and it should 5 (whether straight or curved) lead back from the outermost point of that section to an extension or continuation of the axis of the head end section 2; the last-named section and the other main section 5 preferably having 10 a common axis. In the construction shown in Fig. 1, the guiding and locking sections have a ratio of about 3:1; in Fig. 2, the guiding section is about three times as long as in Fig. 1, and in Fig. 3 it is about two and a half times as long as in Fig. 2. As its name implies, the section 4 serves to guide the materials being pinned together to the locking section 3 during the insertion of the pin, and in this way it facilitates the 20 pinning operation.

Due to their inclination, it will be apparent that the sections 3 and 4 conjointly form a shoulder 8 at the foot of the locking angle which is offset laterally from the common axis of the main sections 2 and 5—or, 25 in other words, which projects outward from said axis; the extent of such offsetting depending not only upon the lengths of the sections 3 and 4 and their angular relation 30 but also upon the size or extent of the aforesaid locking angle. It is to be understood that both sections 2 and 5 may be curved while still maintaining their co-axial arrangement.

In using the pin, it is inserted in the usual way through the pieces to be fastened to

gether, the inclined portion 4 guiding it therethrough while the other inclined portion 3 offers no obstruction to such movement, so that it can readily be effected. On withdrawing the pin, however, the said portion 3 will tend to resist outward movement, and an actual pull must therefore be exerted with some force on the pin in order to cause the portion in question to pass through the material. Hence, this resistance, which can be adjusted by varying the locking angle, as previously explained, will entirely obviate any accidental disengagement of the pin.

The invention as a whole may be regarded as a variation or development of that disclosed in my prior application, No. 120,188, filed July 2, 1926.

I claim as my invention:

1. A pin, embodying a shank which is bent to form head end and point end sections having a common axis, a single locking section extending outwardly at an obtuse angle from the foot of the head end section, and a single guiding section extending inwardly at an angle from the foot of the locking section to the top of the point end section; the guiding section being relatively long as compared with the locking section.

2. A pin, according to claim 1, in which all four sections of the shank lie wholly in a single plane.

In testimony whereof I affix my signature.

HUGO KARL SAKOWSKI.
